(No Model.)

E. S. BATCHELOR.

ELECTRIC GOVERNOR AND INDICATOR FOR FLUID PRESSURE BRAKES.

No. 251,991.

Patented Jan. 3, 1882.

UNITED STATES PATENT OFFICE.

EDWIN S. BATCHELOR, OF PITTSBURG, PENNSYLVANIA, ASSIGNOR TO HIM-
SELF AND CHARLES W. BATCHELOR, OF SAME PLACE.

ELECTRIC GOVERNOR AND INDICATOR FOR FLUID-PRESSURE BRAKES.

SPECIFICATION forming part of Letters Patent No. 251,991, dated January 3, 1882.

Application filed September 14, 1881. (No model.)

To all whom it may concern:

Be it known that I, EDWIN S. BATCHELOR, of Pittsburg, county of Allegheny and State of Pennsylvania, have invented or discovered 5 a new and useful Improvement in Electric Governors and Indicators for Fluid - Pressure Brakes; and I do hereby declare the following to be a full, clear, concise, and exact description thereof, reference being had to the accompanying drawings, making a part of this specification, in which—like letters indicating like parts—

Figure 1 is a view in perspective of a portion of a car-axle and car-truck frame with a portion 15 of my improved appliances arranged in connection therewith, sufficient to illustrate to those skilled in the art its construction and operation. Fig. 2 shows to a reduced scale the same appliances in connection with an axle, a 20 pair of wheels, and a portion of the truck-frame. Fig. 3 is a view in perspective of a pair of the electric-wire couplings which I employ. Fig. 4 is a view in perspective of one such couplings. Fig. 5 is a detached side view, and Fig. 6 is a top 25 or plan view, of the circuit closer and breaker which I employ as an attachment to the operating-cock of a fluid-pressure brake apparatus; and Fig. 7 is a diagram of the wires employed, 30 illustrative of the action in making and breaking circuits.

In the operation of fluid-pressure brakes it sometimes happens that inadvertently or otherwise the engineer turns or sets the operating-cock so as to cause the application of more 35 brake-power than is desired, as a result of which one or more of the wheels may be locked so as to slide on the track, whereby such wheel or wheels is soon materially injured, if not spoiled. Also, the same result is liable to follow 40 from the use in the same train of cars from different roads, since in the absence of a uniform standard of car construction the leverage by or through which brake-power is applied is not always the same.

My present invention is primarily designed 45 to give instant notice to the engineer in case of the sliding of any wheel of his train, and this I can accomplish by the action of a device having some of the features of a centrifugal

steam-governor, which is preferably so combined with an electric circuit that while the train is running at more than a fixed or predetermined minimum speed the axle-circuit makers will be closed, and then when the circuit is closed on the engine by the setting of the operating-cock in applying the brakes, if at such time too much power is applied, and a pair of wheels is caused to slide, the corresponding axle-circuit will be automatically and at once broken, with the result of giving an alarm on the engine. The engineer will then, of course, let off or release such amount or percentage of brake-power as will leave such sliding wheels free to revolve, but without necessarily releasing the brake-power entirely; and with the resumption of rotation the broken circuit will be restored, and the alarm will cease until (if such should be the case) an axle-circuit is again broken by like means.

Each axle A, or those axles the wheels of which are most liable to slide, have loosely fitted thereon—that is, on each—a tapering collar, A', and from two opposite sides thereof project the arms A². To the ends of these arms I secure the connecting-rods a', which extend along a short distance parallel with the axle, and then turn up and unite in a single rod, a, which works through a depending post or hanger, A³, secured to some part—say, the beam A⁴—of the truck-frame. This hanger is 80 of wood or other suitable insulating material.

To the end of the rod a, I connect a rope, a², which passes around the pulley a³, and extends to the end of the car, or to other convenient point. The stems a a' constitute a kind of 85 "draw-frame," and may be so designated.

On the axle A, I arrange a band or collar, B, and make it so tightly on or secure it so firmly to the axle by clamping or otherwise that it will revolve with the axle. This band or collar carries a clip or bifurcated post, B', in which I pivot a governor-arm, G', and to the outer or free end of the arm I attach a comparatively light weight, G, but one heavy enough for doing the work hereinafter described. Two 90 other collars, D D', are also securely clamped on the axle, so as to revolve therewith, and all the three collars B, D, and D' are insulated

from electrical connection with the axle in any suitable way—as, for example, by a sheet of india-rubber, B². Two wires, properly insulated, extend from a battery and circuit-closer on the engine back through the train, one direct and the other through the several apparatuses herein described. Such second wire, s, Fig. 1, on coming to any or each set of the apparatus, passes down the hanger A³, and makes electrical connection with a metallic strip, d, which is always in electrical contact with the collar D'. A wire, s', extends from this collar, beneath the collar D, (insulated therefrom,) and leads to a metallic contact-piece, s², on the end 15 of the governor-lever G. Another metallic contact-piece, s³, is attached to the collar D, and these contact-pieces s² and s³ have such relationship that when the weight G rests on the axle, as shown, contact will be broken, but 20 when the weight G is thrown out away from the axle by centrifugal force by and during the running of the train, or when forced out by the draw-frame a a' and collar A', contact will be made, and a circuit will be formed from 25 the wire s to the collar D. A metallic strip, d', always presses against this collar, and from it a wire, s⁴, leads to the next apparatus, and, in fact, is a part and continuation of the second wire, s, above referred to. Both wires are to 30 be in electrical contact at the rear of the train. The contact-piece s³ is preferably made of spring-metal. A spring, g, is added to the governor-lever G', so as to draw the weight G to the axle in case the axle ceases to revolve 35 when the weight is on the under side of the axle or so far down that its own gravity will not bring it to the axle when the axle stops revolving.

Leaving out of consideration for the present 40 the draw-frame a a', with the devices operating in the immediate connection therewith, it will be seen that as soon as the train in motion acquires a minimum running speed the weight G will be thrown outwardly by centrifugal 45 force until contact is made at s² s³, and such contact will be preserved while the speed is maintained exceeded.

By devices presently to be described the engineer in turning the cock to apply brake-power closes the circuit of the wires referred to. If he applies so much power as to slide any pair of wheels in the train, the weight G on the axle of such pair of wheels will come back to the axle, so as to break the circuit at 55 s² s³, and thereby, through any suitable bell-ringer or other audible or visual signal on the engine, notify the engineer of the fact. He then will at once release a portion of the brake-power or diminish it, so as to free the locked 60 wheels, which, again revolving, will restore the broken circuit and reverse or change the signal.

One suitable form or construction of circuit maker and breaker is illustrated in Figs. 5 and 6, where P may represent a portion of the operating-cock, such as is commonly used in ap-

plying fluid-pressure for braking purposes; and P' is the handle. A strip of wood or other insulating material, b, is secured to the plug or key of the cock, so as to move with it, and 70 a metallic pin, c, having a slight range of vertical motion, but held down by a spring, c', is inserted in the end of such strip. A curved bar, P², is arranged in such position that the end or head of the pin c may slide thereon. A 75 metallic contact-piece, c², is inserted in such part of this bar that the pin c will rest thereon or be in contact therewith when the cock is turned for applying brake-power. One of the circuit-wires—say, s¹⁰—leads to the contact-piece c² and the other, (above called the second one,) s, leads to the pin c. Then when the cock is turned to the position for applying the brakes the circuit will be closed, and when the brakes are off the circuit will be broken; but in the combinations described and hereinafter claimed other suitable forms of circuit makers and breakers may be substituted for those described, provided the essential features of operation remain substantially unchanged. 85

While the electric apparatus on the engine may be varied at pleasure, I have illustrated by diagram in Fig. 7 one suitable arrangement and combination.

At s s¹⁰ I have illustrated the train circuit-wires uniting at s⁶ at the rear of the train to close the circuit at that point, and at s² s³, I have represented the axle-circuit makers and breakers of Fig. 1. The wire s¹⁰ leads through battery e to the contact-piece c², and the wire 90 s to an electro-magnet, e', and thence by wire (here lettered e²) to the pin c, made as in Figs. 5 and 6. The armature c³ has electrical contact by its pivot-post and wire e⁴, through a bell-ringer, g, with the wire s¹⁰, back of the battery. When the armature c³ is free it is drawn back by a spring into contact with a stud, i, which, by wire i', connects with the wire e². Now, assuming the axle-contacts c² c³ to be in contact and the train running, there will be 100 normally no closed circuit, since the brakes, being off the operating-cock, will be in position for broken circuit. If the operator then turns his cock to apply the brakes, he will close the 105 cock contact-pieces c c² and make a complete circuit through the battery e and electro-magnet e'. The armature c³ will then be drawn to its magnet and away from contact with the stud i. If, then, a wheel slides, the corresponding axle-contacts will be separated, as described, which will break the circuit. The 110 armature c³ will then make contact with the stud i, and a new circuit will be formed from battery e through contact-pieces c² c, wires e² i', stud i, armature e³, and wire e⁴, through the 115 bell-ringer g, or other signaling apparatus, so as to actuate the latter and give the proper alarm. The engineer then lessens the brake-power without breaking the circuit at the 120 cock, so that the locked wheels may again revolve and close the broken circuit, and this 125 will result in again charging the electro-mag- 130

net e^3 , and by drawing over the armature will break the bell-ringing or other signaling circuit and leave the apparatus in condition for giving another alarm or signal in case of the 5 sliding of the same or another pair of wheels.

The structure in detail of the apparatus (shown only in the diagram) is well known, so that a lengthy explanation is unnecessary; but for the mere purpose of giving an alarm or signal other arrangements of known devices may 10 be substituted.

For coupling the circuit-wires between cars I employ the devices shown in Figs. 3 and 4, where R represents a coupling block or head, 15 made of wood or other suitable insulating material, and having a shank or stem, r, by which it may be suspended from the car-body in case the wires are not heavy enough for such function, and each block having a pin, r' , projecting from its face a little to one side of its center, or a little to one side of the middle of its end face. On each side of each block is a U-shaped metallic plate, n, arranged on the block, so that one leg, n' , shall lie neatly alongside of 20 pin r' (and a like one on the other side) and the other leg, n^2 , is bent to a bow shape, and sufficiently for the opposite legs of two plates to come in contact with each other when not forced apart; and this double bow is made on 25 the side of the axial or center line of the block, opposite the pin r' , and at the same distance from such axial or center line. The wires $s^1 s^2$ are brought to the opposite sides of the stem or shank r, and led along to make contact each 30 with a plate, n. One of these couplings or one half-coupling is thus connected with the circuit-wires at each end of the car, so that when cars are run together to make up a train the pin r' of each half-coupling may be slipped between the spring-plates of legs n^2 of the other 35 half, as a result of which each leg n' on the side of the pin r' will be in electrical contact with a leg, n^2 , of the opposite half-coupling, and as the half-couplings thus made are duplicates of 40 each other, any two of them may be connected or coupled together. Hence each line of wires 45 will be electrically insulated as against the other line, except at the rear of the train, where the bow-shaped legs n^2 from opposite sides of 50 the block R will be in contact and complete the circuit at that point, as required at e^6 , Fig. 7.

To prevent the half-couplings from pulling apart, as against ordinary or usual strains, 55 pins o may be provided on the sides of pins r' , which will enter holes o' in the legs n^2 when two half-couplings are united.

Returning, now, to the draw-frame a a' and collar A', these are merely appliances added for convenience in ascertaining before a train 60 starts out whether or not the electrical apparatus is in good condition. For this purpose the rope a^2 is pulled, so as to shift the draw-frame a a' to the left, and thereby slide the collar A' along beneath the weight G, and by 65 raising the weight tilt the arm G' till the contact-pieces $s^2 s^3$ are in contact. To hold it there

in each apparatus till all such contacts are made throughout the train, I provide a spring-hook, z, and beveled catch z' in such position that when the draw-frame a a' is so drawn to 70 the left and contact is made the hook z will engage the catch.

In order, now, that when the electrical circuits are found to be all right the apparatus may be restored to normal working position, 75 I add a trip-bar, v, so that normally its lower end will be out of the way of the governor-arm G', a light spring, v', serving to hold it up; but in moving the draw-frame a a' to the left, as above described, the beveled upper end of 80 this trip-bar, passing under the stiff spring-hook z, will be forced down by the side of the governor-arm G', or so that its lower end will be in the path of such arm when it begins to move with the axle. As soon as the train 85 starts the arm G', in moving around with the axle, will strike the lower rounded end of the trip-bar v and force it upward against the under side of the spring-hook z, while the latter is caught on the catch z'. This results in free- 90 ing the hook from its catch, and a spring, z'', on the stem a forces the draw-frame back to the right, and the apparatus is then in normal working position.

It may happen, perhaps once in a hundred 95 times, that when a train is just made up and ready to be tested as above the trip-bar v may be directly above the governor-arm G', as shown in Fig. 1. In such case the draw-frame a a' must be drawn a little farther than otherwise, 100 so that the trip-bar may be forced down past the end of the governor-arm. Then, as soon as the train starts and the arm G' moves away from the trip-bar, it with the draw-frame will come back to the position before described— 105 that is, with the lower end of the trip-bar in the path of the governor-arm—with the result of disengaging catch and hook as before. The same or like arrangement of circuits, circuit makers and breakers, and electrical appliances 110 may be employed as a brake-governor to indicate or signal to the engineer when a maximum speed has been attained; but in such case the spring g, which holds or tends to hold the governor-weight G to the axle, should be made 115 strong enough to overcome the centrifugal tendency of the weight during all speeds below such maximum, so that only when such maximum is reached or exceeded will the contact-pieces $s^2 s^3$ come in contact to complete the 120 circuit. Of course in such use of the invention the wire connections should be closed at all other points. To secure greater accuracy and certainty of operation means should be added such as are well-known in the art for adjusting 125 the power of the spring.

I claim herein as my invention—

1. The combination of a centrifugal governor, a car-axle, an electrical make-and-break mechanism operated by the governor, an electrical circuit extending thence to the engine, and an audible or visual signal in such circuit 130

in convenient position for signaling the engineer, substantially as set forth.

2. The combination of an electrical wire-circuit extending along any desired part of the train, an axle-governor, a make-and-break mechanism actuated by such governor, a valve-operating mechanism, and a make-and-break mechanism operated by the valve motion, substantially as set forth.

12 3. The combination, in a railway-train, of an electric-wire circuit, a centrifugal governor taking its motion from an axle, an electric make-and-break mechanism actuated by such governor, a spring tending to hold said governor to the axle, and a signal or alarm, substantially as set forth.

4. The combination, on a railway-train, of an electric-wire circuit, a centrifugal governor taking its motion from the axle, a make-and-break mechanism actuated by the governor, a valve-operating mechanism, a make-and-break mechanism operated by the valve motion, and a bell-ringing and signaling circuit brought into operation by the breaking of the previously-closed train or main circuit, substantially as set forth.

25 5. The insulated collars D D' B and strips d d', in combination with circuit-wires and with a centrifugal governor actuated from the car-axle, and a make-and-break mechanism actuated from such governor, substantially as set forth.

6. In combination with a centrifugal govern-

or and axle, the draw-frame a a', collar A', hook z, catch z', and trip-bar v, as a means for testing apparatus of the class described, substantially as set forth.

7. The combination of a railway-train signal, a signaling electric circuit, a valve mechanism for applying fluid-pressure brake-power, and an electrical make-and-break mechanism operated in making and breaking the circuit by the valve motion, substantially as set forth.

8. An electrical coupling having in combination in each half a block, R, and pin r' of non-conducting material, a metallic plate, n, 45 on each side of the block, a leg, n', having a projection, o, of each plate n lying along each opposite side of the pin r', and a perforated leg, n², of each plate n bent to a bow shape so as to make contact with the opposite leg n² of the same half-coupling when the couplings are disconnected, but such legs n² being arranged to be separated by the pin r' of the other half-coupling when two half-couplings are united, and at the same time make electrical contact 55 with the legs n' of such other half, substantially as set forth.

In testimony whereof I have hereunto set my hand.

EDWIN S. BATCHELOR.
